HAT RETAINING DEVICE

Mortimer J. Solomons, New York, N. Y.

Application October 18, 1938, Serial No. 235,552

6 Claims. (Cl. 132—61)

This invention relates to new and useful improvements in a hat retaining device.

The invention proposes the construction of hat retaining devices characterized by the provision of an elastic loop for attachment to a lady's hat and having a hairpin supported thereon in a novel manner to be engaged into the hair in a particular manner for holding the hat on the head.

Still further it is proposed to provide the hairpin with a loop portion at its back end through which the elastic loop is adapted to be passed.

Another object of this invention is to form the elastic loop from a length of elastic material, doubled in half, and having its ends securely attached together and inserted between the adjacent faces of the headsize band and the lower portion of the crown of the hat.

Still further it is proposed to provide a means for releasably connecting the elastic loop to the hat in such a manner that the entire loop and hairpin may be removed therefrom when desired.

Another object of this invention is the provision of a means for releasably connecting the elastic loop to a clip which in turn is adapted to be releasably connected with the hat in a particular manner.

A still further object of the invention is the provision of a handle member, formed in the hairpin, to facilitate the removing of the hairpin from the wearer's head.

For further comprehension of the invention, and of the objects and advantages thereof, reference will be had to the following description and accompanying drawing, and to the appended claims in which the various novel features of the invention are more particularly set forth.

In the accompanying drawing forming a material part of this disclosure:

Fig. 1 is a rear elevational view of a head and a hat having a hat retaining device constructed according to this invention.

Fig. 2 is a sectional view taken on the line 2—2 of Fig. 1.

Fig. 3 is a perspective view of the hat retaining device per se.

Fig. 4 is a view similar to a portion of Fig. 2 illustrating a modification of the invention.

Fig. 5 is a perspective view of the hat retaining device used in connection with the modification shown in Fig. 4.

Fig. 6 is a perspective view of the clip per se.

Fig. 7 is a front elevational view of a hat re-

taining device constructed according to a still further modification of the invention.

Fig. 8 is a sectional view taken on the line 8—8 of Fig. 7.

Fig. 9 is a perspective view of one of the ends of the elastic loop.

Fig. 10 is a similar view to Fig. 3, but illustrating another form of hairpin.

The hat retaining device, according to this invention, includes an elastic loop 10 for attachment on a lady's hat 11 in the vicinity of the headsize band 12. The elastic loop 10 is constructed from a length of elastic material having its ends securely attached together by means of stitches 13 passing therethrough. The secured ends of the loop 10 are adapted to be inserted between the adjacent faces of the crown of the hat 11 and the headsize band 12, preferably one at each side or at the back of the hat. After the loop has been inserted between the adjacent faces of the headsize band and the crown of the hat the headsize band 12 may be secured in position in the customary manner by means of stitches 14 which will also pass through the ends of the loop 10, maintaining them fixedly in position.

A hairpin 15 is slidably engaged upon the loop 10 and is adapted to be inserted into the hair for maintaining the hat 11 in position upon one's head. The pin 15 is formed with a looped portion 15a through which the elastic loop 10 freely engages.

The operation of this form of the invention is as follows:

The hat 11 is first properly positioned upon the head, the pin 15 is grasped in the fingers in the vicinity of the loop portion 15a and pulled outward and downward, stretching the elastic loop 10. The pin 15 is then turned to direct the front ends thereof towards the hair permitting the resiliency of the elastic loop to urge the pin 15 into the hair for maintaining the hat in position upon the head.

According to the modification of the invention shown in Figs. 4 to 6 inclusive, a clip 16 having an opening 16a is provided with clamp portions 16b which are adapted to be attached upon the ends of the elastic loop 10. As shown in Fig. 6 the clamp portion 16b consists of a rectangular extension formed on one side of the clip 16 and which is adapted to be rolled around the ends of the elastic loop 10 in the manner shown in Fig. 5.

With this construction it is possible to releasably connect the elastic loop 10 with the hat 11.

so that it may be removed therefrom when desired. This releasable connection is accomplished by means of a snap fastener 17. One element 17^a of the snap fastener 17 is secured 5 to the inside face of the crown of the hat. The other element 17^b of the snap fastener 17 is securely attached to the adjacent face of the headsize band 12 (see Fig. 4). The headsize band in the vicinity of the snap fastener element 10 17 is free from the crown of the hat with the stitches 14' extending completely around the hat, except for the area in the vicinity of the snap fastener 17. In the engaged position of the snap fastener elements 17^a and 17^b there is sufficient space between the adjacent faces thereof, 15 as shown in Fig. 4, to permit the clip 16 to be inserted therebetween.

In other respects this form of the invention is similar to the previous form.

20 According to the modification of the invention shown in Figs. 7-9 inclusive a clip 16' consists of a portion having the opening 16^a and which continues into a base section 16^c. A separate top section 16^d is adapted to be releasably connected 25 with one of the faces of the base section 16^c. This attachment is accomplished by means of headed pegs 18 which extend from the base section 16^c and which engage through slots 19 formed in the ends of the top section 16^d.

30 The ends of the elastic loop 10'' have rectangular elements 20 of felt or similar material securely attached thereto by means of stitches 21. The rectangular elements 20 are adapted to be inserted and clamped between the adjacent faces of the 35 base section 16^c and the top section 16^d when the pegs 19 are engaged into the bayonet slots 19. The top section 16^d is formed with a plurality of inwardly extending prongs 16^{dd} which are adapted to engage into and frictionally maintain the rectangular elements 20 in position between the adjacent faces of the base section 16^c and the top section 16^d.

The operation of this form of the invention is as follows:

45 The top section 16^d is removed from the base section 16^c by disengaging the pegs 18 from the bayonet slots 19. After this removal the rectangular elements 20 are positioned upon the face of the base section 16^c between the pegs 18. The 50 top section 16^d is then positioned upon the rectangular elements 20 with the prongs 16^{dd} thereof engaging into the elements 20 permitting the pegs to be re-engaged into the openings 19 for fixedly holding the rectangular elements 20 in position upon the base section 16^c. In other respects 55 this form of the invention is similar to the previous forms.

In Fig. 10 the hairpin 15' is illustrated with a looped portion 15^{aa} formed integrally with and 60 at one side of the hairpin 15', so that the loop 15^{aa} projects inwardly and is in the same plane with the plane formed by the two side portions of the hairpin. In this form of the invention the connecting portion 15'' of the hairpin extends beyond the loop portion 15^{aa} so that it may be readily gripped and used as a handle for removing the hairpin from the wearer's head. The loop 15^{aa} also acts as an abutment for the opposite side of the hairpin to ascertain that the free ends of the 65 hairpin, are spaced from one another.

70 It is to be understood that any desired number of hairpin units may be used, for retaining the hat in position and that the length, color and construction of the elastic loop may also be varied 75 as desired.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new, and desire to secure by United States Letters Patent is:

1. A hat retaining device, comprising an elastic loop for attachment on a lady's hat in the vicinity of the head-size band, and a hairpin supported on said loop, a clip having an opening and clamp portions attached on the ends of said loop, and a fastener on said hat and coactable with said clip and opening for releasably holding the loop. 15

2. A hat retaining device, comprising an elastic loop for attachment on a lady's hat in the vicinity of the head-size band, and a hairpin supported on said loop, a clip having an opening and clamp portions attached on the ends of said loop and a fastener on said hat and coactable with said clip and opening for releasably holding the loop, said clamp comprising a rectangular extension formed 20 on one side of said clip and which is adapted to be rolled around the ends of said elastic loop. 25

3. A hat retaining device, comprising an elastic loop for attachment on a lady's hat in the vicinity of the head-size band, and a hair pin supported on said loop, a clip having an opening and clamp portions attached on the ends of said loop, and a fastener on said hat and coactable with said clip and opening for releasably holding the loop, said clamp comprising a rectangular extension formed on one side of said clip and which is adapted to be rolled around the ends of said elastic loop, said fastener comprising a snap fastener element having sufficient space between the adjacent faces of its elements for accommodating 30 the thickness of said clip. 35

4. A hat retaining device, comprising an elastic loop for attachment on a lady's hat in the vicinity of the head-size band, and a hair pin supported on said loop, a clip having an opening and clamp portions attached on the ends of said loop, and a fastener on said hat and coactable with said clip and opening for releasably holding the loop, said clamp comprising a rectangular extension formed on one side of said clip and which is adapted to be rolled around the ends of said elastic loop, said fastener comprising a snap fastener element having sufficient space between the adjacent faces of its elements for accommodating the thickness of said clip, said clamp comprising a base section, a separate top section formed with inwardly extending prongs, rectangular elements mounted on the ends of said elastic loop and engageable between the adjacent faces of said base section and said top section with said prongs engaging therein, and a means for releasably fastening said top section to said base section. 50 55

5. A hat retaining device, comprising an elastic loop for attachment on a lady's hat in the vicinity of the head-size band, and a hair pin supported on said loop, a clip having an opening and clamp portions attached on the ends of said loop, and a fastener on said hat and coactable with said clip and opening for releasably holding the loop, said clamp comprising a rectangular extension formed on one side of said clip and which is adapted to be rolled around the ends of said elastic loop, said fastener comprising a snap fastener element having sufficient space between the adjacent faces of its elements for accommodating 70 75 80 85 90 95 98

the thickness of said clip, said clamp comprising a base section, a separate top section formed with inwardly extending prongs, rectangular elements mounted on the ends of said elastic loop and engageable between the adjacent faces of said base section and said top section with said prongs engaging therein, and a means for releasably fastening said top section to said base section, said means comprising headed pegs extending from 10 said base and engaging beneath slots formed in said top section.

6. A hat retaining device, comprising an elastic

loop, a hairpin supported on said loop, rectangular elements mounted upon the ends of said loop, a clamp for engagement upon said rectangular elements for completing said loop to prevent said hairpin from disengaging therefrom, a fastener mounted upon a hat, and a clip formed on said clamp and engageable with said fastener for connecting said loop to said hat so that said pin may be inserted into one's hair to prevent said hat from being blown off one's head. 10
